INVENTOR

UNITED STATES PATENT OFFICE

98,412

DESIGN FOR A DRESS

William S. Woolfe, New York, N. Y., assignor to Franklin Simon & Co., Inc., New York, N. Y.

Application December 31, 1935, Serial No. 60,350

Term of patent 3½ years

To all whom it may concern:

Be it known that I, William S. Woolfe, a subject of Great Britain, residing in Manhattan, county of New York, and State of New York, have invented a new, original, and ornamental Design for a Dress, of which the following is a specification, reference being had to the accompanying drawing, forming part thereof, wherein,

The diagonal lines on the front and back portions of the sleeves represent drawn-work within an area edged with braid.

I claim:

The ornamental design for a dress, substantially as shown, and described.

WILLIAM S. WOOLFE.
